UNITED STATES PATENT OFFICE.

JOSEPH S. DUNCAN, OF CHICAGO, ILLINOIS, ASSIGNOR TO ADDRESSOGRAPH COMPANY,
OF CHICAGO, ILLINOIS, A CORPORATION OF ILLINOIS.

ENVELOP-FEEDING MECHANISM.

1,063,336.

Specification of Letters Patent.

Patented June 3, 1913.

Application filed January 15, 1910. Serial No. 538,187.

To all whom it may concern:

Be it known that I, JOSEPH S. DUNCAN, a citizen of the United States, residing at Chicago, in the county of Cook and State 5 of Illinois, have invented new and useful Improvements in Envelop-Feeding Mechanism, of which the following is a specification.

This invention relates to improvements in 10 envelop feeding machines and comprises certain novel and useful improvements on the machine disclosed in my application Serial No. 480,598 filed March 1, 1909.

The object of this invention is to provide means of simple character for automatically and quickly feeding envelopes in a regular and orderly manner from a supply to an addressing machine, or for other purposes.

20 The invention also has for its object to provide a machine for feeding envelopes of different sizes and different thicknesses; to insure feeding the envelopes singly and at regular intervals; to provide means of simple character for adjusting to a fine degree the throat through which the envelopes are fed from the supply; to operate the drawing roll positively and intermittently and provide means to permit the drawing roll to 25 revolve freely by reason of the frictional engagement of the envelop therewith as it is being withdrawn from the supply; to provide means for engaging and feeding the envelop from the supply after the drawing 30 roll which has partly fed the envelop from the supply has ceased to be positively operated; and to yieldingly support and accurately adjust the presser rolls.

The invention has other objects in view 40 which will more clearly appear hereinafter in the detail description, reference being had to the accompanying drawings in which—

Figure 1 is a plan view of a machine embodying the invention. Fig. 2 is an elevation of the front or feed end of the machine. Fig. 3 is an elevation looking at the right side of Figs. 1 and 2. Figs. 4 and 5 are sectional views on the lines 4—4 and 5—5, 50 respectively, of Fig. 2. Fig. 6 is a detail of one of the presser rolls and the envelop supporting finger adjacent thereto. Fig. 7 is a detail of the throat member adjusting mechanism. Fig. 8 is a detail sectional view

showing particularly the means of adjustment for the throat member plate. Fig. 9 is a view on the line 9—9 of Fig. 2 showing the pawl and ratchet connection on the shaft 25.

Referring to the drawings, the main shaft 60 is mounted in suitable bearings (not shown) in the machine frame 8 and a gear 9 is mounted on the main shaft and is adapted to drive a gear 10 which is rigidly mounted upon the shaft 11 mounted in suitable bearings in the frame. A plurality of feed rolls 15 is mounted upon the shaft 11 and these feed rolls are spaced apart a suitable distance and each is provided with a peripheral groove adapted to receive tapes 13 which 65 feed the envelop or other article to be printed toward the rear of the machine. Each of the feed rolls comprises a plurality of feeding sectors 14 one on each side of the tape groove in the roll, the remainder of 70 the periphery of the roll being sufficiently recessed to avoid operative engagement with an envelop as it is fed from the supply. A shaft 16 is journaled in a frame 17 which is pivoted at 17' at either side of the main 75 frame 8 and this shaft carries a presser roll 18 (Fig. 6) disposed opposite to each feed roll 15. These presser rolls are constructed to oppose the feed sectors on the feed rolls and to press the envelop in engagement 80 with said sectors. Means are provided for yieldingly supporting the presser roll in operative position and for adjusting the presser roll to work of different kinds. For this purpose an adjusting bolt 19 is arranged through the lower portion of the 85 presser frame 17 and through an opening in a lug 20 on the main frame. A spring 21 is arranged on the bolt 19 and by its expansive force tends to yieldingly thrust the 90 presser rolls into operative relation to the feed rolls. The operative position of the presser rolls to the feed rolls may be regulated by adjusting the bolt 19.

The stack of envelops is supported in the 100 machine at the front, nearest the operator, by an inclined adjustable shelf 22, by the drawing roll 23 at the throat 24, and by the vertically adjustable supporting roll 25 between the shelf and drawing roll. The 105 shelf is secured to or mounted on the main frame by rods 26 which enter bearings 27 in the frame, one of these bearings being made

to form a clamp (Fig. 1) and provided with a thumb nut 28 by which said clamp can be securely tightened on the rod therein to hold the shelf in adjusted position. For 5 end alinement of the stack of envelops I employ a vertical rod 29 which is secured to a slotted base 30 (Fig. 2) and which may be adjusted laterally of the machine and secured in adjusted position by a thumb nut 31 (Fig. 1).

The supporting roll 25 is mounted on a shaft 25' which is journaled in suitable bearings in a frame 32 and this frame is pivotally mounted on the shaft 23' which carries the drawing roll 23, said shaft 23' being itself journaled in suitable bearings in the main frame of the machine. The frame 32 is secured rigidly in adjusted position by a thumb nut 33 which passes through a projection 34 on the frame and through a vertical slot 35 in the stud 36 which projects upward from the main frame (Figs. 1 and 2). This construction permits of the vertical adjustment of the roll 25 relative to the roll 23.

The throat member 37 has rearwardly extending arms 38 which are pivotally mounted at 39 on the arms 40 of the main frame. This throat member is sustained in operative relation to the drawing roll by means which are also adapted to provide for a fine adjustment of said member. The throat member comprises upwardly extending arms 41 which are notched at their upper ends 42 for the reception of the adjusting rod 43. This rod is mounted in eccentric bearings 44 in the arms 40 and the arms 41 are held in operative relation to the adjusting rod by one or more leaf springs 45. An adjusting device comprising a plate 46 has its hub 47 secured on the end of the rod 43 (Fig. 7) and is provided with a slot 48 eccentrically disposed to the pivot of the plate to receive the set-screw 43'. The adjusting plate has a handle 49 and a scale 50 of any suitable character on its edge. An index pointer 51 is arranged on the main frame opposite the scale. By adjusting the plate 46 the adjusting rod 43 is caused to move in its eccentric bearings, and by reason of the eccentrically disposed slot in the adjusting plate and the eccentric bearings of the rod a very fine adjustment of the throat member is enabled. The foregoing adjustment may be found sufficient for all practical purposes but I prefer to provide the throat member with an adjustable throat plate 52 (Fig. 4) which is arranged in a recess 53 in the throat member. A plurality of bolts 54 operate in the throat member and are tapped into the throat plate to adjust the plate and hold it in place, and additional bolts 55 operate through the throat member and bear upon the throat plate to provide for a more accurate adjustment and to coöperate with

the bolts 54 to lock the throat plate in its adjusted position. This throat plate is of especial importance to provide a throat of uniform width throughout its length. Owing to wear or other causes the normal parallel relation of the throat member proper and the drawing roll may be disturbed and provide a throat of varying width, but this can be readily overcome and the uniformity of width of the throat member restored by adjusting the throat plate.

The feed rolls 15 and the presser rolls 18 are continuously driven, the gear 10 on the feed roll shaft 11 driving the gear 10' mounted on the presser roll shaft 16. However, the feed rolls are adapted to feed intermittently by reason of the feeding sectors thereon, as previously explained, to provide time for the printing operation. For the same reason it is desirable to operate the drawing roll intermittently and for this purpose I provide the shaft 11 with a loose gear 56 which drives the idle gears 57, 58, the latter in turn driving a gear 59 on the drawing roll shaft 23'. The latter gear 59 drives an idle gear 60 which in turn drives the gear 61 loosely mounted on shaft 25' of the supporting roll (Fig. 3). A ratchet 62 (Fig. 5) is mounted on the hub 56' of the gear 56 and an arm 63 rigidly mounted on the shaft 11 carries a pawl 64 which engages the ratchet 62. The pawl is held in engagement with the ratchet by a spring 65 which is attached at one end to the pawl and at its other end to a pin 66 rigid with the shaft 11. The shaft 11 operates continuously, and to disengage the pawl from the ratchet so that the gear 56 may operate intermittently I provide the free end of the pawl with a laterally projecting pin 67 which engages a stationary cam 68 loosely mounted on the shaft 11. The cam 68 has a laterally extending hub 68' on which an arm 69 is mounted, this arm having a laterally extending pin 70 which engages the main frame (Fig. 2). The cam 68 is secured in its properly adjusted position by a set screw 71 which passes through the collar of the arm 69 and rigidly secures the cam and arm together. The cam floats on the shaft 11 and is held against rotation with the shaft by the engagement of the arm 69 with the main frame. The arm 63 and the pawl 64 revolve with the shaft 11 and the spring 65 holds the pawl in engagement with the ratchet until the pin 67 on the pawl rides up on the high part of the cam 68 whereupon the pawl is lifted out of engagement with the ratchet. While the pawl is in engagement with the ratchet the gear 56 is operated to revolve the drawing and supporting rolls but when the pawl is disengaged from the ratchet the positive movement of these rolls ceases so that an intermittent action of the drawing and supporting rolls is secured.

porting rolls is provided to correspond with the intermittent feeding action of the feed rolls.

The feed rolls operate at a higher rate of speed than the drawing roll and as the envelop may be caught by the feed rolls before it leaves the drawing roll, this being the usual provision, it is desirable to permit the drawing and supporting rolls to operate freely on their shafts at this time at the higher rate of speed so that the envelop may, in effect, be snapped away from the drawing roll by the more rapidly operating feed rolls. For this purpose the gear 59 (Fig. 3) is loosely mounted on the shaft 23' and is provided with a spring-pressed pawl 72 which engages a ratchet 73 rigid with the drawing roll shaft 23'. The gear 61 is likewise loosely mounted on the shaft 25' and is provided with a spring-pressed pawl 75 adapted to engage a ratchet 76 fast on the shaft 25'. Thus while the envelop is being fed into and partly through the throat the drawing and supporting rolls will operate at their normal rate of speed but when the envelop is caught by the feed rolls which operate at a higher rate of speed than the drawing roll and supporting roll, they are permitted to rotate under the frictional engagement of the envelop therewith at or about the higher rate of speed of the feed rolls and independently of the gear 59, by reason of the pawl and ratchet connections between the supporting roll shaft, drawing roll shaft and their driving gears. The parts are so timed that while the feed rolls are actually feeding an envelop the gear 56 and the chain of gears operated thereby are at rest.

40 A plurality of guard fingers 74 are provided on the frame (Figs. 4, 6) and extend upward between the drawing roll and the presser rolls and projecting into grooves 18' in the presser rolls (Fig. 6) prevent the envelopes from falling out of their proper path of travel.

While my improved feeding machine is particularly adapted for feeding envelopes it is capable of being used for feeding paper, 50 cards, and similar things and it may be employed for feeding such things to a printing machine or for other purposes.

The invention provides a simple mechanism for feeding envelopes and the like one 55 at a time from a pile and delivering them intermittently to a printing or other mechanism so that time will be afforded for printing or other operations incidental to the feeding movement. The feeding roll operates at a comparatively high rate of speed to deliver the envelopes quickly from the mechanism and this feeding operation is intermittent for the purpose explained. The 60 operation of the drawing roll is intermittent so that it will be positively driven up to or

about the time the feeding roll takes hold of the envelop and at this time, owing to the fact that the feeding roll is driven faster than the drawing roll is positively driven, provision is made for permitting the drawing roll to revolve at a greater rate of speed 70 for the reason that the envelop, at this time, will still be in engagement with the drawing roll and thus the drawing roll is permitted to revolve freely as fast as the envelop 75 travels while the envelop is being fed by the feed rolls. Thus the envelop is permitted to travel as fast as the drawing roll revolves until the envelop is engaged by the feed rolls and then the drawing roll is permitted to travel at a higher rate of speed corresponding 80 to the rate of speed of the feed rolls. This prevents the envelop from being pulled away from the drawing roll by the feed rolls faster than the drawing roll revolves which would have a tendency to retard the movement of the envelop and increase the work of the feed rolls.

The adjustments for the throat member and the throat plate are important to provide a throat of proper and uniform width throughout its length to accommodate the envelopes or other things on which the mechanism is working. Thus provision is made for readily adjusting the mechanism to envelopes or other things of different thicknesses. The presser roll can be readily adjusted and after being set to the work will automatically adjust itself as occasion requires.

What I claim and desire to secure by Letters Patent is:

1. In a feeding mechanism of the class described, the combination of a continuously rotated feed roll, an intermittently operated 105 drawing roll, a driven gear loosely mounted on said drawing roll, connections between said gear and the drawing roll permitting a rotary movement of the drawing roll in one direction independently of the gear, a 110 driving gear loosely mounted on the feed roll, a train of gears connecting said driving and driven gears, and means for intermittently connecting said driving gear with the feed roll to impart a rotary movement to 115 said drawing roll.

2. In a feeding mechanism of the class described, the combination of a continuously operated feed roll, a driving gear loosely mounted thereon, a drawing roll, a driven 120 gear loosely mounted thereon, pawl and ratchet mechanism for connecting said driven gear to the drawing roll, means for operatively connecting said driven gear with said driving gear, and means for intermittently connecting the driving gear to the continuously rotating feed roll whereby an 125 intermittent rotary movement is imparted to the drawing roll.

3. In a feeding mechanism of the class de- 130

scribed, the combination of a continuously rotating feed roll, a drawing roll, a supporting roll, a driven gear loosely mounted on said drawing roll, connections between 5 said driven gear and the drawing roll connections between said driven gear and the supporting roll, whereby both of said rolls are operated from the driven gear, each of said connections permitting each roll to rotate in one direction independently of the movement of the driven gear and of each other.

4. In a feeding mechanism of the class described, the combination of a continuously 15 rotating feed roll, a drawing roll, means for connecting said drawing roll to the feed roll, a supporting roll and means for connecting said supporting roll to the drawing roll, whereby the supporting and drawing rolls 20 may be operated from the feed roll and are capable of rotary movement independent of said feed roll and of each other, and means for controlling the connection between the feed roll and the drawing roll to automatically 25 establish and break the connection between said rolls.

5. In a feeding mechanism of the class described, the combination of a continuously 30 rotating feed roll shaft, a gear loosely mounted thereon, a ratchet integral with said gear, a pawl mounted to travel with the shaft and adapted to engage said ratchet, stationary means for controlling the operation of said pawl, whereby the connection 35 between said shaft and said gear is automatically and intermittently established and broken, a drawing roll, and operative connections between said drawing roll and said gear.

40 6. In a feeding mechanism of the class described, the combination of a continuously rotating shaft, a gear loosely mounted thereon and provided with ratchet teeth, an arm secured on said shaft, a pawl pivoted 45 on said arm and adapted to engage with the ratchet teeth on said gear, a stationary cam controlling the operation of said pawl to intermittently disconnect the gear from said shaft, a drawing roll, and operative connections 50 between said roll and said gear.

55 7. In a feeding mechanism of the class described, the combination of a shaft, a gear provided with a ratchet loosely mounted thereon, a drawing roll driven from said gear, an arm rigidly secured to said shaft, a pawl pivoted on said arm to engage said ratchet, a cam loosely mounted on said shaft; and adapted to actuate said pawl, means for preventing rotation of the 60 cam, and means for angularly adjusting said cam, whereby to vary the time of actuation of the pawl by said cam to disconnect the gear from said feed roll.

65 8. In a feeding mechanism of the class described, the combination of a shaft carry-

ing a plurality of feed sectors, an integral gear and ratchet-wheel loosely mounted on said shaft, an arm rigidly secured to the shaft, a pawl carried by said arm and adapted to engage with said ratchet-wheel, a floating cam carried on said shaft, and a connection between said cam and said pawl whereby the pawl is lifted out of operative engagement with the ratchet-wheel to disconnect the gear from the feed roll shaft.

9. In a feeding mechanism of the class described, the combination of a drawing roll, a supporting roll, a driving connection between said drawing and supporting rolls for rotating said supporting roll while permitting it to rotate independently of the drawing roll, and means for supporting said rolls whereby one of said rolls is capable of angular adjustment about the other roll.

10. In a feeding mechanism of the class described, the combination of a drawing roll, a pivotally mounted throat member, a throat plate adjustably mounted on said member, and means for positively moving the throat plate on the throat member toward and from 90 said drawing roll.

11. In a feeding mechanism of the class described, the combination of a drawing roll, a pivotally mounted throat member, a throat plate carried thereby, means for imparting to said member and plate a conjoint arcuate movement about the pivot of the member, and means for imparting an independent rectilinear adjusting movement to the plate.

12. In a feeding mechanism of the class described, the combination of a drawing roll, a pivotally mounted throat member, a throat plate adjustably mounted on said member, means for adjusting said member and plate conjointly, and means for adjusting the plate relatively to the member to vary the distance between the outer edge of said plate and the pivot of said member.

13. In a feeding mechanism of the class described, the combination of a pivotally mounted throat member comprising upwardly extending arms, said arms being notched and each notch having one yielding wall, an eccentrically journaled rod arranged to operate in said notches, and means for adjusting said rod to adjust said throat member.

14. In a feeding mechanism of the class described, the combination of a throat member having rearwardly extending pivoted arms and upwardly extending notched arms, and means for adjusting said throat member and sustaining the same in adjusted position comprising an eccentrically journaled rod arranged to operate in said notches, and means for adjusting said rod.

15. In a feeding mechanism of the class described, the combination of a pivotally mounted throat member, an eccentrically

journaled rod positively engaged with said throat member to adjust the same, and means for adjusting said rod comprising a pivoted adjusting plate having a slot disposed eccentric to the pivot of said plate to receive said rod.

16. In a feeding mechanism of the class described, the combination of a pivotally mounted throat member having upwardly extending notched arms, and means for adjusting the throat member and sustaining it in adjusted position comprising an eccentrically journaled rod arranged to operate in said notches, and means for operating said rod comprising a pivoted plate having a slot eccentric to the pivot of the plate to receive the rod.

17. In a feeding mechanism of the class described, the combination of a drawing roll, a shaft carrying said roll, a supporting roll adjacent to the drawing roll, a frame pivotally mounted on the drawing roll shaft and carrying said supporting roll, and means for locking the frame in adjusted position.

18. In a feeding mechanism of the class described, the combination of a main frame, means for supporting the envelops in the frame comprising a drawing roll mounted in the frame, a supporting roll vertically adjustable relative to the drawing roll, and an inclined shelf adjustable relative to said rolls.

19. In a feeding mechanism of the class described, the combination of a main frame, inclined circular bearings on said frame, one of said bearings being made to form a clamp, an inclined shelf, and supporting rods connected to said shelf and adapted to be inserted in the bearings on the frame, whereby they may be adjusted longitudinally therein to position the shelf, and may be held in the desired position by the said clamp.

20. In a feeding mechanism of the class described, the combination of a main frame, a feed roll having a tape-receiving groove on its periphery, a tape adapted to operate in said groove, a grooved presser roll adapted to contact with said feed roll upon either

side of said tape groove, means for adjusting the position of said presser roll, and a device secured on the main frame and extending into the groove in the presser roll for guiding the article to be fed into position between said feed roll and presser roll.

21. In a feeding mechanism of the class described, the combination of a continuously rotating feed roll, a drawing roll, driving mechanism normally connected with said drawing roll, means for intermittently connecting the driving mechanism with the feed roll for actuating said driving mechanism to cause an envelop to be delivered by said drawing roll to the feed roll, the connection between said drawing roll and driving mechanism permitting said drawing roll to assume a peripheral speed equal to the speed of the feed roll when an envelop is withdrawn from said drawing roll.

22. In a feeding mechanism of the class described, the combination of a continuously rotating feed roll, a train of gears, means for intermittently connecting said gears with the feed roll, a drawing roll adapted to be operated by said train of gears, a supporting roll also adapted to be operated by said train of gears simultaneously with said drawing roll, and connections between said train of gears and said drawing and supporting rolls whereby said rolls are permitted to revolve in one direction at a speed greater than the speed of the train of gears to permit an envelop to be withdrawn by said feed roll from a supply.

23. In a feeding mechanism of the class described, the combination of a continuously rotating shaft, a drawing roll, operative connections between said roll and shaft, a gear provided with a ratchet loosely mounted on said shaft, a pawl fixed to said shaft in position to engage said ratchet, and means for controlling the position of said pawl whereby said gear is automatically and intermittently fixed relatively to said shaft.
